UNITED STATES PATENT OFFICE

WALTHER DALHEIMER, OF EINDHOVEN, NETHERLANDS, ASSIGNOR, BY MESNE ASSIGNMENTS TO RADIO CORPORATION OF AMERICA, OF NEW YORK, N. Y., A CORPORATION OF DELAWARE

WIRE BENDING MECHANISM

Application filed October 8, 1926, Serial No. 140,369, and in the Netherlands November 27, 1925.

This invention relates to means for bending wires and more particularly for bending wires several times through a determined angle.

Means for bending wires are already known. With these known means bending is mostly ensured by the use of a stencil or a punch with a matrix. The wire may be simply bent around a corner. If a wire is to be given several bends, several movements are in this latter case required for this purpose. The use of a punch and matrix obviates this inconvenience, but it is difficult in this case to vary the distance between the two bends.

According to the invention the wire is gripped by holders which are given such a motion relatively to each other that the distance between the two adjacent gripping points of the holders remains unchanged. The advantage of this arrangement is that by a simultaneous movement of the holders the wire is bent twice, any kink in that part of the wire which is comprised between the bends is avoided and by a readjustment of a holder a change in length of said part of the wire is easily made.

One embodiment of the invention comprises a movable and a stationary holder and during its motion the movable holder moves or swings in an arc of a circle having as its radius the length of that portion of the wire between the holders. This arcuate motion can be realized constructively in various ways but preferably the movable holder comprises a member on which there are three points each of which is connected by an arm or link to a fixed pivot. The length of each of the three arms or links is equalized with the length of that part of the wire between the holders. It is desirable that the arms or links should be adjustable to vary in a simple manner the distance between the two bends of the wire.

For holding the wire the movable holder may be provided with an aperture in which the wire can be inserted or the movable holder may have mounted on it a chuck comprising an adjustable stop and a sliding clamping jaw, the arrangement being such that

the wire is clamped between this clamping jaw and the stop. In the former case it is impossible to change the position of the gripping point of the movable holder relatively to that of the stationary holder. This inconvenience has been obviated by providing an adjustable stop with a clamping piece.

In an embodiment of the invention in which the wires are bent twice at right angles the adjacent sides of the movable as well as of the stationary holder are flat and parallel to each other, the movable holder being so moved that after the bending operation at right angles the said sides bear on each other.

This arrangement is applicable to bending supporting- and leading-in wires of stems of electric lamps, electron discharge tubes and similar electric devices. In such devices the leading-in wires are sealed in the stem and subsequently they are bent into a determined position so as to permit of the filament being attached. In the case of electron discharge tubes the anode has sometimes to be brought into a definite position relatively to the pinched portion or press of the stem and in that case it may be necessary for the anode supporting wires to be bent twice at right angles.

One device serving to bend the leads and supporting wires of such stems comprises various movable holders each of which is intended for one of the wires. If some of the supporting wires have to be bent oppositely to the other supporting wires one part of the holders is given a clockwise and the remaining part an anti-clockwise motion.

The accompanying drawings illustrate an embodiment of the invention. In the said drawings Figures 1, 2, 3 and 4 represent diagrammatically the positions of the various holders during the operation upon the wire; Figure 5 is a longitudinal section of the wire chuck shown in Fig. 4; Figure 6 shows diagrammatically another position of the holders; Figure 7 is a side view of a suitable construction in which the supporting wires and leading-in wires of the stem of a thermionic valve are bent at right angles to each side; Figure 8 is a bottom view of the construction.

of Fig. 7, and Figures 9 and 10 are perspective views of a thermionic valve stem prior and subsequent to the bending operation.

In the first six figures like reference numerals indicate similar parts. 1 and 2 indicate the jaws of a stationary wire chuck, and 3 is a movable member provided with a wire holder, such as an aperture 4, for receiving and holding a wire 5. The member 3 is movably mounted by means of pivoted arms or links 6 each connected at one end to stationary studs 7 and at the other end to pins 8 in the member 3 so as to permit this member 3 to swing or describe an arc about the stationary studs 7.

When the wire 5 is fed the chuck jaws 1 and 2 remain open until the wire has been inserted in the holder or aperture 4 of the member 3. The jaws 1 and 2 are then closed as shown in Figure 2 and the member 3 is swung about the studs 7, and so follows an arcuate path of about 90° around the studs 7 into the position shown in Figure 3. The distance between the pins 8 and the studs 7 is equal to the distance between the member 3 and the jaws 1 and 2, and hence to the length of the free portion of the wire 5, thus ensuring that during the swing or travel of the member 3 along its arcuate path the distance between the gripping points of the jaws 1 and 2 and the member 3 remains unchanged and any kink in the wire is avoided.

A different construction is shown in Figures 4, 5, and 6 in which the movable member 3 is provided with a wire chuck comprising an adjustable stop 9 and a movable jaw 10. The adjustable stop 9 is provided with slots 11 to permit it to be moved over the adjusting bolts 12. The movable jaw 10 is provided with two studs 13 that guide it in a slot 14 in the member 3. A lug 15 on the jaw 10 is connected by a spring 16 with a stud on the member 3 so that the jaw 10 is resiliently held against the stop 9. In Figure 4 and in Figure 6 this wire chuck is shown in two different positions. In Figure 4 the position is such that the clamped portions of the wire in the jaws 1 and 2 and in the jaws 9 and 10 are in alignment with each other. In Figure 6 a position is shown in which these two clamped portions are out of alignment but parallel to each other. This construction permits slight variations in the length of wire intermediate the bends.

In Figures 7 and 8 is shown a suitable construction by which a plurality of wires 33 sealed into the press of the stem 18 of a thermionic valve (Figure 9) are each bent twice at right angles and some are bent to one side of the press and others to the other side. For this purpose two movable members or holders 21 and 22 are mounted like the movable member 3 beside the jaws 19 and 20 of a stationary chuck for holding the wires 33. To hold each wire these movable members

may be provided with an aperture, as shown in Figs. 1, 2, and 3, or with a stop and jaw as shown in Figs. 4, 5, and 6. The two movable members shown in Figures 7 and 8 hold the projecting ends of the wires 33 by means of wire holding apertures 23 and 24 (Figure 8) provided in prongs which project from the adjacent ends of the members 21 and 22 and are so positioned as to overlap. To swing each of the movable members or holders in an arcuate path like that of the member 3 in Figs. 1, 2, and 3, each of said movable members 21 and 22 is provided with pins 28 and 29 which by means of arms or links 27 are connected to stationary studs 25 and 26. The two movable members 21 and 22 are swung apart or moved away from each other to bend some of the wire 33 in one direction and others in the opposite direction, as shown in Figure 10. To swing them apart the members may have rollers 30 and 31 which bear on the flat sides of an actuating wedge 32. As the wedge moves in the direction of the arrow in Figure 7 the movable members 21 and 22 are driven apart and each swings through an arcuate path about the fixed studs 25 and 26. As a result of this separation of the members 21 and 22 part of the support wires 33 of the thermionic valve stem 18 are bent to the left and the remainder to the right, as shown in Fig. 10. As the wedge 32 moves in the opposite direction the movable members 21 and 22 are returned to their original position by a spring 34 which tends to pull them together.

What I claim is:—

1. A wire bending device comprising a stationary chuck for holding the wire, a movable member having at least one pair of pivots, arms mounted upon said pivots to permit said member to swing upon said arms, a second chuck mounted upon said member in alignment and spaced from the first chuck and comprising a slidable spring pressed jaw, and means to move the member.

2. A wire bending device comprising a stationary chuck for gripping the wire, a member mounted to swing along an arcuate path, pivots on said member, arms mounted upon said pivots, a second chuck mounted upon said member in alignment with and spaced from the first chuck and comprising one adjustable jaw and one slidable spring pressed jaw, and means to move the member.

3. A wire bending device comprising a stationary wire gripping chuck consisting of a pair of movable jaws, a member mounted to swing along an arcuate path, a pair of pivots on said member, arms mounted upon said pivots, a second chuck upon said member in alignment with and spaced from the first chuck and consisting of one adjustable jaw and one slidable spring pressed jaw, and means to move the member.

4. A wire bending device comprising a stationary chuck for gripping the wire, a member mounted to swing along an arcuate path, at least one pair of pivots on said member, arms mounted upon said pivots, a second chuck mounted upon said member in alignment with and spaced from the first chuck, the distance between the first and second chuck being equal to the distance between centers of the pivots of said arms, and means to move the member.

5. A wire bending device for bending a plurality of wires in different directions comprising a stationary chuck for holding all the wires, a plurality of members mounted for parallel movement in different directions, a plurality of wire holders on each member in alignment with and spaced from the stationary chuck and each adapted to hold one wire, and means to move said members.

6. A wire bending device for bending a plurality of wires in different directions comprising a stationary clamp for gripping all the wires, a plurality of members each having pivots and mounted for movement in different directions, arms mounted upon the pivots on said members to give the members parallel movement, a plurality of wire holders on each member in alignment with and spaced from the stationary clamp and each adapted to grip one wire, and means to move said members.

7. A wire bending device for bending a plurality of wires in different directions comprising a stationary clamp for gripping all the wires, a pair of members mounted for parallel movement in opposite directions, a plurality of wire holders in each member in alignment with and spaced from the stationary clamp and each adapted to grip one wire, and means to move said members.

8. A wire bending device for bending a plurality of electrode supporting wires comprising a stationary clamp for gripping all the wires, a pair of members mounted for movement in opposite directions and each having pivots, arms mounted upon the pivots on said members to give the members parallel movement, a plurality of wire holders upon each member in alignment with and spaced from the stationary clamp and each adapted to hold one wire, and a cam for engaging and moving said members.

9. A wire bending device for bending a plurality of electrode supporting wires comprising a stationary clamp for gripping all the wires, a pair of members mounted for movement in opposite directions and each having pivots, arms mounted upon the pivots on said members to give the members parallel movement, a plurality of wire holders upon each member in alignment with and spaced from the stationary clamp and each adapted to hold one wire, a cam for engaging said

members to move them, and a spring to keep the members in contact with the cam.

10. A wire bending device for bending a plurality of electrode supporting wires comprising a stationary clamp for gripping all the wires, a pair of members mounted for movement in opposite directions and each having pivots, arms mounted upon the pivots on said members to give the members parallel movement, a plurality of wire holders upon each member in alignment with and spaced from the stationary clamp and each adapted to hold one wire, a reciprocating cam engaging both members and pressing them in opposite directions, and a spring to return the members to the original position.

11. A wire bending device for bending a plurality of electrode supporting wires comprising a stationary chuck having two movable jaws for gripping all the wires, a pair of pivoted members mounted for movement in opposite directions, arms mounted upon the pivots of said members to give the members parallel movement, and a plurality of wire holders upon each member in alignment with the stationary chuck and spaced therefrom and each adapted to hold one wire.

12. A wire bending device for bending a plurality of electrode supporting wires comprising a stationary clamp for gripping all the wires, a pair of members mounted for movement in opposite directions and each having pivots, arms mounted upon the pivots on said members to give the members parallel movement, a plurality of clamps upon each member in alignment with and spaced from the stationary clamp and each adapted to grip one wire, a spring pressed jaw for each of said plurality of clamps, and a cam for engaging the members to move them.

13. A wire bending device for bending a plurality of electrode supporting wires comprising a stationary clamp for gripping all the wires, a pair of pivoted members mounted for movement in opposite directions, arms mounted upon pivots on said members to give the members parallel movement, a plurality of clamps upon each member in alignment with and spaced from the stationary clamp and each adapted to grip one wire, a spring pressed jaw for each of said plurality of clamps, and an adjustable jaw for each of said plurality of clamps, and a cam for engaging the members and moving them.

14. A wire bending device comprising a stationary chuck for holding a plurality of wires, two wire holders mounted to register with and engage different wires held in said chuck and each movably mounted to move in an arcuate path transversely of the wire engaged by it and to remain during its movement along its path parallel to said chuck, and common actuating means for moving said holders away from said chuck in oppo-

site directions to bend two of said wires in opposite directions.

15. A wire bending device comprising a stationary chuck for holding a plurality of wires side by side, two movable holders mounted to register simultaneously with said chuck and engage different wires held in said chuck and to move in parallel arcuate paths transverse to the wires in said chuck and to
- 16 remain parallel to said chuck during their movement along their paths, and common actuating means for moving said holders simultaneously away from each other and out of registry with said chuck whereby the wires engaged by said holders are bent in opposite directions.

In testimony whereof I affix my signature at the city of Eindhoven, this 21st day of September, A. D. 1926.
